DESIGN FOR A CALENDAR

Frank Steuwer, Cincinnati, Ohio

Application February 3, 1941, Serial No. 98,713

Term of patent 7 years

To all whom it may concern:

Be it known that I, Frank Steuwer, a citizen of the United States of America, residing at Cincinnati, in the county of Hamilton and State of Ohio, have invented a new, original, and ornamental Design for a Calendar, of which the following is a specification, reference being had to the accompanying drawing, forming part thereof, wherein the figure is a perspective view of the calendar, showing my new design, the back of the same being plain.

I claim:

The ornamental design for a calendar, as shown and described.

FRANK STEUWER.
